UNITED STATES PATENT OFFICE.

JOSHUA C. CONRAD, OF CEMENT, OKLAHOMA.

COTTON-MACHINE.

1,058,846.

Specification of Letters Patent.

Patented Apr. 15, 1913.

Application filed February 9, 1912. Serial No. 676,500.

To all whom it may concern:

Be it known that I, JOSHUA C. CONRAD, a citizen of the United States, residing at Cement, county of Caddo, and State of Oklahoma, have invented certain new and useful Improvements in Cotton-Machines, of which the following is a specification.

My invention relates to improvements in cotton machines and particularly to a combined hulling and cleaning machine.

The object of my invention is to provide a machine which shall be adapted to thoroughly clean cotton whether the same be picked from the boll or with the boll.

15 A further object of my invention is to provide a machine of the character and for the purpose mentioned in which the cotton which has been picked from the boll may or may not be subjected to the same treatment necessary for that picked with the boll, to the end that the cotton may be put in the best condition for ginning.

20 A further object of my invention is to provide a boll cotton cleaning machine in which the mechanism may be adjusted for various conditions of the cotton supplied to the device.

Other objects will appear hereinafter.

With these objects in view my invention 30 consists generally in a vacuum box provided at its lower end with an air valve which also constitutes a cotton discharging device, a substantially vertical screen partition dividing the box into two chambers each communicating with said valve, a feed duct leading into said box, valves for directing the cotton from said duct into either of said chambers as desired, an air duct leading from one of said chambers, boll crushing 35 and segregating mechanism in the last mentioned chamber and a co-acting screen interposed between said mechanism and the air duct.

40 My invention further consists in a cotton cleaning device characterized as above stated in which one of the valves is formed of screen and when in position to direct the cotton to the chamber containing the boll crushing mechanism, shall constitute a continuation of the screen between said mechanism and the air duct and when in position to direct the cotton into the other chamber, shall constitute a continuation of the screen partition.

45 My invention further consists in a cotton cleaning machine as above mentioned in

which the screen co-acting with the crushing and segregating mechanism shall be adjustable toward or from said mechanism.

50 My invention further consists in various details of construction and arrangements of parts all as will be fully described herein-after and particularly pointed out in the claims.

55 My invention will be more readily understood by reference to the accompanying drawings forming a part of this specification and in which—

Figure 1 is a vertical longitudinal section through a cotton cleaning machine embodying my invention in its preferred form. Fig. 2 is a side elevation of the same, and Fig. 3 is a detailed section, taken on substantially the line α — α of Fig. 1.

60 Referring now to the drawing 1 indicates the vacuum box which is supported by a suitable frame 2. Leading into the front of the box adjacent its upper end is a duct 3 through which the cotton is fed to the device, the inner end of the duct being flared 65 as at 4 to distribute the cotton evenly throughout the width of the box. Extending from the rear of the box, that is the opposite side from the duct 3, is an air duct 5 leading to the fan or vacuum creating device. The lower end of the box terminates 70 in a cylindrical shell or casing 6 in which is rotatably mounted an air valve 7 controlling the cotton discharge port or opening 8.

75 The valve 7 comprises a pair of end spindles 9 connected by a plurality of radially disposed boards 10 forming a series of pockets 11. To the outer edges of the boards 10 are secured flexible strips 12 which engage the walls of the shell 6 and prevent an upward draft through the port 8.

80 A vertical transverse partition 13 is arranged in the box 1 dividing the same into chambers 14 and 15. The partition 13 is formed of screening and extends from substantially on a level with the bottom of the duct 3 to adjacent the valve 7, the lower end being so arranged that both chambers are 85 in communication with the valve shell 6. 16 and 17 indicate transverse frame members 90 forming braces or supports for the screen partition 13.

95 Arranged in the chamber 15 is the boll crushing and segregating mechanism. This 100 comprises a crushing cylinder 18 and co-acting concave 19 together with a plurality of beaters 20 and a co-acting screen 21. The

cylinder 18 is of heavy cast iron construction and provided on its peripheral face with diagonally disposed ribs or lugs 22. The concave 19 comprises a yieldingly supported member 23 having a concave face adjacent the cylinder 18 to which is secured cast plates provided with ribs or lugs 24 similar to the lugs 22 and adapted to co-act therewith. The concave 19 is supported by rods 25 extending through frame members 26, and springs 27 interposed between the members 23 and 26 hold the concave yieldingly in position. 28 indicates a nut on the rod 25 for limiting the inward movement 10 of the concave and serving as means whereby the normal position of the same with relation to the cylinder may be regulated. The beaters 20 comprise wooden cylinders 29 provided with a large number of radially projecting pins or spikes 30. The screen 21 extends from the lower edge of the concave 19 to the upper adjacent edge of the valve shell 6 and is shaped to conform to the crusher cylinder and the beaters throughout 15 about half of the circumference of the latter. The beaters are preferably arranged one above the other as shown in Fig. 1 and the screen therefore comprises a series of superimposed substantially semi-cylindrical portions 25 between the adjacent edges of which are arranged brace members 31. The screen 21 and brace members 31 are secured to substantially vertical members 32 which lie flat against the sides of the box 1 and which 30 are hingedly mounted at the bottom as at 33, by which construction the screen may be adjusted toward or from the beaters as desired. The members 32 are provided with slots 34 through which extend thumb screws 35 for securing the device in adjusted position. Extending over the crusher cylinder 18 for a short distance from the upper edge of the concave toward the inlet 3 is a short screen section 36. It will be noted that the 35 section 36 forms a substantial continuation of the screen 21 and said screen 21 is arranged between the crushing and segregating mechanism and the air dust 5.

The bottom of the box beneath the screen 21 is inclined as at 37 and at the lower edge of the incline 37 is formed a channel 38 in which is arranged a screw conveyer 39. The bottom portion 37 is hinged as at 40 and constitutes a door whereby access may be 45 had to the screen 21 for adjusting, repairing, or removing the same.

Hingedly mounted at the lower edge of the inner end of the duct 3 is a valve 41 which is preferably solid or imperforate, 50 and to the upper edge of the duct is secured a valve 42 which is formed of screening and which when in one position forms a continuation of the screen 21 and in another position a continuation of the screen 13. The 55 valves 41 and 42 are operated by levers 43

and 44 and if preferred these levers may be connected by suitable means 45 whereby they may be operated simultaneously.

The shafts of the cylinder 18 and beaters 20 are provided with pulleys 46 and 47 respectively which are coupled by belting 48, 49 and 50 as shown. The shaft of the cylinder 18 is also provided with a pulley 51 for the power belt not shown. 52 indicates the pulley for the belt for driving the rotary 75 air valve 7.

The operation of the device is as follows: A partial vacuum is created in the box 1 through the duct 5 and the cotton to be cleaned is drawn thereby through the duct 80 3. If the cotton has been picked from the bolls the valves 41 and 42 are dropped into the position shown in full lines in Fig. 1, unless dirty and trashy, in which event the cotton will pass through the chamber 14 to 85 the valve 7 and thence through the port 8 to the gin or elsewhere as desired. As the cotton passes through the chamber 14 is drawn against the screen 13 and the dust and dirt is separated therefrom by being 90 drawn through said screen. It should be noted that the screen 42 forms a continuation of the screen 13 thereby increasing the area of the cleaning surface.

Should the cotton fed to the device be in 95 the bolls, or dirty or trashy, the valves 41 and 42 are raised as indicated in dotted lines thereby causing the cotton to pass into the chamber 15 to be acted upon by the boll crushing and segregating mechanism. The 100 valve 41 across which the cotton passes, being imperforate, prevents any of the dirt from dropping through the chamber 14 to the valve, and the valve 42 forms a continuation of the screen 21. As the cotton passes 105 between the cylinder 18 and concave 19 the bolls are crushed and as it passes between the beaters 20 and the adjacent portions of the screen 21 it is segregated and the dust and dirt together with portions of the bolls 110 are drawn through the screen to be carried away by the duct 5 or the conveyer 39.

This device may be used as an unloader or circulating machine as valves 7 will discharge in an air space as well as in the 115 open.

Having described my invention what I claim as new and desire to secure by Letters Patent:

1. A device of the class described, comprising a vacuum box, a valved discharge at the lower end thereof, an inlet adjacent the upper end of the box, an air duct leading from the opposite side of said box from said inlet a substantially vertical screen partition dividing said box into two chambers, a pair of valves, a connection between said valves for operating the same simultaneously to direct the cotton from said inlet into either of said chambers, each of said 120 125 130

chambers communicating at its lower end with said valved discharge, boll crushing and segregating mechanism in the chamber in direct communication with said air duct, 5 and a screen co-acting with said segregating mechanism and adjustably mounted between the same and said air ducts, substantially as described.

2. A device of the class described comprising a vacuum box, a screen partition dividing said box into two chambers a valved discharge in communication with the lower end of each of said chambers, an inlet leading into said box above the upper end of 10 said partition, valves for directing the cotton from said inlet into either of said chambers as desired, an air duct leading from one 15

of said chambers, boll crushing and segregating mechanism in the last mentioned chamber, a screen interposed between said mechanism and said duct, one of said valves being imperforate and the other valve being foraminated and in one position forming a continuation of said screen partition and in another position a continuation of the 20 screen between the segregating mechanism and the air duct, substantially as described.

In testimony whereof I have signed my name to this specification in the presence of two subscribing witnesses.

JOSHUA C. CONRAD.
